SECTIONAL CASING CONSTRUCTION

Charles B. Akers, Akron, Ohio

Application April 21, 1939, Serial No. 269,136

1 Claim. (Cl. 189—34)

The present invention relates to the construction of metal structures in which a wall or casing is composed of sections or panels united by battens or the like in a complete structure. The invention was originally designed for use in the manufacture of casings about furnace or boiler structures in order to obviate certain disadvantages of former devices of this nature, the casing being attached to the main supporting structure, the intermediate space behind the casing being filled with an insulating material. However, the principles of the invention may be applied to partitions, wall, or ceiling structures and many different devices of a similar nature.

The usual and accepted devices have the disadvantage that the bolts securing the battens to the main supporting structure have projected through the battens and are thus exposed on the outside of the wall structure. This is not only unsightly but the projecting bolts will rust and work loose. In addition, adequate provision is not made for expansion and contraction of the wall, consequently the bolts or holding devices soon become insecure.

Other objects and advantages will be apparent from the further description contained herein, the invention being illustrated in its best known or preferred form, and being subject to modifications and adaptations within the scope of the claim.

In the drawing, in which the preferred embodiment of the invention is shown:

Fig. 1 is a cross section through a portion of the casing made in accordance with the invention showing intermediate or flat battens and corner battens with the panels mounted therein. This view also shows, by way of example only, studding for carrying the casing. This view is taken on the line 1—1 of Fig. 2.

Fig. 2 is a front elevation fragment of the casing,

Fig. 3 is a cross section through a horizontal batten, on the line 3—3 of Fig. 2.

In the drawing, 1 represents the plates or panels which constitute the main body of the casing structure. In furnace casings or similar installations these plates or panels are made of sheet metal, either plain or corrugated in their central areas, but wood, ply-wood, or other material may be substituted where such material may be desirable. The complete casing is made of any number of these panels, supported and held together as a wall unit by means of interposed battens, the battens being attached to the main structure or to a frame work or studding as de-

sired. In the illustration of the invention, studding is shown merely as an example of how the structure may be built up.

Vertical battens such as employed in the main body of the wall are shown at 2, while corner battens are illustrated at 3. Horizontal battens which may or may not be attached to the supporting structure are shown at 4. In case of the corner battens, the central portion is bent on the angle required. For battens at ceilings and floors, 10 similarly formed battens may be used.

The studding or supporting structure is here illustrated as a rigid framework consisting of vertical posts 6 and bracing members 7, but this is by way of example only, as any part of the 15 main supporting structure may be employed for this purpose.

The battens consist of a main plate 8, preferably formed of sheet metal, having a central area along the batten indicated by the numeral 9 20 which is presented to the front of the structure. At the sides the plate is reversely bent or folded to provide longitudinal channels along the edges of the battens indicated by the numeral 10, the edges of the plate terminating in the two parallel wings 12. In the channel thus provided between the face of the plate and wings 12, the edges of the panels 1 are received and frictionally held.

Extending across the rear of each batten are a 30 number of straps or braces 15, the ends of which are folded inwardly to provide channels or grooves 16 which receive the wings of the battens. The connection between the straps and the battens is intended to be a close fit with sufficient 35 friction to hold the battens in place, but to allow for shifting sufficiently to allow for the expansion and contraction of the parts. Similarly, the fit between the panels and the battens permits movement between the parts for the same purpose, and in this connection the turned down ends of the straps may bear against the rear walls of the panels to assist in frictionally holding the panels against the sides of the batten channels and prevent looseness of the panels 45 while allowing for expansion and contraction of the entire wall structure.

The securing means for the wall structure is seated in the strap and while any style of holding means may be employed, bolts 20 may be used 50 as shown, projecting through the main web of the strap and secured on the inner side thereof by nuts 21. In the form shown, the bolts pass through the upright members of the studding 6 and are clamped by other nuts 22. When the 55

wall structure is to be secured directly to the main structure, such, for instance, as a furnace or boiler, the securing means should be modified. While no securing means is shown for the horizontal battens, similar means may be employed.

In the corner battens 3 the bridge pieces or straps 25 are necessarily shortened to span the angle across the rear face of the battens as shown to the left in Fig. 1, otherwise the construction follows the pattern of the intermediate battens already described.

It will be observed that the securing means is located wholly at the rear of the battens and that no part thereof projects in the outer face 15 of the wall or casing. This is an important element of the invention as it not only improves the appearance but also protects the ends of the securing means from rusting or deterioration from the outside of the casing. The heads of the 20 securing means by which the battens are secured to the supporting structure, in this case the nuts 21, are received in the space at the rear of the battens between the inner extremities of the channels. By providing this chamber to receive the securing means, it is possible to employ ordinary bolts to secure the casing to the main supporting structure. This facilitates the easy assembly of the device. It will also be observed 25 that the outer face of each batten is integral

with the main body and is not a mere cover piece for the panel holding means.

While the means extending across the rear of each batten to afford anchorage for the wall structure is shown as individual bridge pieces 5 spaced at requisite intervals, it will be understood that these bridge pieces may be enlarged and indeed be coextensive with the battens themselves.

What is claimed is:

A wall structure comprising a supporting structure located rearwardly of the wall, a plurality of spaced battens each of which is formed of a single sheet having a central imperforate web portion and side channels formed by inwardly 15 extending reversely bent edge portions, the bottoms of said channels being spaced apart, individual panels forming the main body of the wall and having their edges frictionally held in the channels, a bridge piece across the rear 20 of a batten having inturned flanges gripping the edges of the batten and bearing against the panels, and bolts extending from the supporting structure and having their outer ends received in the space between the bottoms of said channels and between the bridge piece and the inner 25 face of the batten.

CHARLES B. AKERS.
